(57) **CLAIM**

The ornamental design for a support head for video and/or photographic apparatuses, as shown and described.

DESCRIPTION

FIG. 1 is a top, front and right side perspective view of a support head for video and/or photographic apparatuses showing my present design;

FIG. 2 is a front elevational view thereof;

FIG. 3 is a rear elevational view thereof;

FIG. 4 is a left elevational view thereof;

FIG. 5 is a right elevational view thereof;

FIG. 6 is top plan view thereof;

FIG. 7 is bottom plan view thereof; and,

FIG. 8 is a top, rear and left side perspective view thereof.

The portions of the article in broken lines are shown for illustrative purposes only and form no part of the claimed design.
